FIG. 1 is a top, rear, and right side perspective view of a bottle showing our new design;

FIG. 2 is a front elevational view thereof;

FIG. 3 is a rear elevational view thereof;

FIG. 4 is a right side elevational view thereof;

FIG. 5 is a left side elevational view thereof; and,

FIG. 6 is a top plan view thereof.

The dot-dot-dot-broken lines shown in the drawing views is included for the purpose of showing environmental structure that forms no part of the claimed design.

The -dot-dash-dot-broken line shown in the drawing views defines the boundary of the claimed design.
